UNITED STATES PATENT OFFICE

2,588,611

COSMETIC CONTAINER

Frederick M. Breen, White Plains, N. Y.

Application March 26, 1948, Serial No. 17,241

1 Claim. (Cl. 132—82)

1

This invention relates to combined containers or compacts suitable for cosmetics and is herein disclosed in some detail as embodied in a combined powder or rouge or cream holder and lipstick holder.

It is generally the practice for powders or creams to be carried in relatively large mouthed pans or cans to enable a user to gather up the material as on a suitable swab or puff, as the case may be, and the covers of the pans or cans are usually tight-fitting and circular. Often the tops are screwed on, or held frictionally sufficiently tight to protect the contents from deterioration, and it is often difficult to properly seize the relatively thin top to rotate it to the extent needed or otherwise open the container.

The lipstick holder is mostly a relatively narrow cylinder, and is herein disclosed as mounted on the cover and adapted to form a handle for the cover of the compact or container adapted to be held by the fingers thus enabling the cover to be turned or otherwise opened easily even if held on by strong friction or suction.

Thus the cover, including the lipstick holder, is thick enough to be grasped in the hand and thus greatly facilitate the opening or closing of the powder container. That is true even if the pan of the compact is thin, since the cover, at least, is easily held.

As a result the user finds her lipstick holder in a convenient place, and the compact in an easily used form.

The device illustrated is conveniently molded out of any one of a number of kinds of plastic, and the lipstick holder may be so designed that it adds almost no weight to the compact beyond the necessary weight of a separate holder. In fact, by reason of the strengthening effect of the molded-on cover part, the holder cylinder and the flat cover mutually strengthen each other, and at the same time make a convenient unit of all essential elements, yet occupying no excess space.

Other features and advantages will hereinafter appear.

In the accompanying drawings:

Fig. 1 is an exploded side view of the device, mostly in section on the line 1—1 of Fig. 3.

Fig. 2 is a side view of the device closed, on a smaller scale.

Fig. 3 is a top view of the same.

Fig. 4 is an end view of the same.

Fig. 5 is a view showing how the device fits the hand in closing or opening.

In the form shown the device includes a bottom member or pan 10 having an upturned flange

2

11 adapted to fit into the depression 12 of a top member 13, and surrounding a powder holding depression 14 in the pan member 10.

The top 15 of the flange 11 is adapted to lie against the ceiling 16 of the depression 12 to form a tight fit and at the same time the horizontal annular shelf 17 is adapted to be brought against the horizontal annular rim 18 of the top member 13.

10 In the form shown the top 15 and shelf 17 are carried into position by threads 18a projecting from the inner face 19 of the boundary wall of the depression 12 which are engaged by external threads 20 on the outer face of the flange 15 as the pan member 10 is turned on the top member 13. The threads 18a and 20 may be interrupted and so pitched that less than a quarter turn of the pan 10 seats its flange top 15 against the ceiling 16.

20 The bottom 21 of the pan member 10 may be flat, but the upper face of the top member 13 is shown as arched at 22, and as further swelled out or enlarged at 23 to provide a covering for a transverse, longitudinal opening or cavity 24 adapted to receive a lipstick 25, for example, and to support the lipstick in the opening 24 by the base (usually metal or synthetic resin) 26 on which the lipstick 25 is mounted.

In the form shown, the opening 24 is separated 30 at its bottom from the depression 12 by a wall 27, which may be thinner than the bottom wall 28 of the pan 10, and the sides of the swelling 23 may be of about the same thickness. The opening 24 extends a short distance beyond the 35 center of the top from its mouth, and may be rounded off at its closed end 29.

The exterior of the swelling as shown springs 40 from the edge of the top member 13 and rises and spreads until the sides are of adequate thickness around the opening 24, and the arch 22 rises about a third of the diameter of the opening, so that at the summit the arch 22 is only slightly undercut. It will be observed that the end of the swelling is spaced above the arch 22, this arrangement facilitating gripping the swelling to effect removal of the cover. The opening 24 may be slightly inside the edge of the top member 13, so that the end of usual milled head 30 of the lipstick mounting 26 lies substantially above the 50 edge of the pan 10. The milled head 30 is itself of advantage in affording a grip on the lipstick and swelling jointly when removing the cover.

The device provides not only a small combined compact and holder, but also provides an easily 55 opened device when the pan 10 is used to hold

semi-liquid cream or other cosmetic which tends to seal the edges 15 and tends to keep a vacuum as the parts begin to be separated. The firm grasp on top and bottom given by the present invention enables the device to be opened easily despite the pressure resulting from the vacuum.

Having thus described one embodiment of the invention in some detail, what is claimed is:

A circular container adapted to hold paste or powder, a threaded flange projecting above the side of the container, an annular shelf outside of the flange, a cover for said container, said cover having an opening, threaded walls bounding the opening against which the flange is adapted to lie, a ceiling against which the top of the flange is adapted to strike, and a transverse swelling on the top adapted to be grasped by the fingers to turn the cover on the threads, said transverse swelling merging at one end thereof with the upper surface of the cover and being spaced above the upper surface of the cover at the other end thereof to facilitate manual access between the cover and said one end of said transverse swelling.
